UNITED STATES PATENT OFFICE.

GEORGE E. MILLER, OF ETNA, PENNSYLVANIA.

TAP.

Application filed November 27, 1922. Serial No. 603,458.

To all whom it may concern:

Be it known that I, GEORGE E. MILLER, a citizen of the United States, residing at Etna, in the county of Allegheny and State 5 of Pennsylvania, have invented new and useful Improvements in Taps, of which the following is a specification.

My invention relates to taps, and its principal object is to provide improved means 10 for automatically collapsing and expanding the threading-dies thereof. In the particular embodiment shown I have applied my invention to the tap shown and described in my Patent No. 1,342,754, granted to me 15 June 8, 1920.

Referring to the accompanying drawings, Fig. 1 is a side elevation of a tap containing my improvements; Fig. 2, a side elevation of the tap rotated axially forty-five 20 degrees from its position shown in Fig. 1, with a part shown in longitudinal section; Fig. 3, a central longitudinal section of my improvements with a portion broken away; Fig. 4, a longitudinal section on a different 25 plane from that of Fig. 3, parts being omitted from the right-hand portion; Fig. 5, a longitudinal section on a plane including the cross-pin; and Fig. 6, a perspective view of one of the dogs or catches for locking the 30 dies in their working position.

On the drawings, 1 is the spindle of a tapping machine having the bearing 2 and the flange 3 to which the flange 4 on the body 5 of the tap is secured by bolts, one 35 marked 6 being shown.

The body 5 has a number of longitudinal holes 7, opening laterally at their front ends into the slots 8 containing the threading dies or chasers 9, and at their rear ends into the slots 10 which receive the arms 11 of the slides 12 which are movable lengthwise in the holes 7. The body 5 is surrounded by the adjusting collar 13 having the internal circular groove 14 to receive the outer ends 40 of the arms 11, whereby, when the collar is moved forwardly from the position shown in the drawings, it will push the slides 12 also. The latter have their outer faces inclined and dovetailed to the dies 9 in the usual manner, so that the slides 12 will when moving outwardly push the threading dies outwardly into working position, and when moving inwardly will pull the dies inwardly to their collapsed position. The cap 14' is 45 secured to the front end of the body 5 by

the screws 15 and form a front wall for the dies 9.

The body 5 is provided with the lugs 16, each supporting a cutter 17 for operating on the ends of the articles at the conclusion of 50 threading operations, 18 representing the screws for holding the cutters in the lugs.

The apparatus so far as now described is the same as shown in my said patent, but the present invention is not necessarily combined with the precise apparatus of the said 55 patent.

19 is a collar slidable on the body 5 between the flange 4 and the lugs 16. The collar 19 has a front threaded portion 20 on which the rear end of the collar 13 is screwed to provide a means for adjusting the throw of the slides 12 and consequently the throw of the dies 9. The body 5 is provided with the slots 21 for the cross-pin 75 22 which has its ends seated in the slots 23 in the front end of the portion 20 of the collar 19 and beneath the threaded part of the collar 13. The pin is biased to the rear end of the slots 21 by the spring 24 in the axial hole 25 in the rear end of the body 5. One end of the spring is fastened to the pin and the other is secured to the screw 26 which extends through the bushing 27 in the inner end of the body 5 and is provided with the nut 28 bearing on the outer face of the bushing.

The body 5 has two diametrically opposite slides 29 having their rear ends beveled rearwardly and toward the axis of the 90 body 5 and lying beneath the collars 13 and 19, but terminating rearwardly near the radial holes 30 which extend from the periphery of the collar 19 to the grooves 31, in which the slides 29 work. These grooves 95 have abrupt rear ends or shoulders 32. Dogs or catches 33 have radial movements in the holes 30 and have the rear faces of their inner ends movable into the grooves 31 and are engageable with the shoulders 32 to lock 100 the collars 13 and 19 and their slides 12 and the dies 9 in their outermost positions. The catches are pressed inwardly by the springs 34 seated in holes in the catches and resting against the flange of the cap 35 105 which telescopes over the collar 19 so as to cover the outer ends of the holes, the disk portion of the cap covering the rear sides of the holes. The cap is secured to the collar 19 by the screws 36. The catches have 110

their inner ends beveled on their front sides to correspond with the bevel on the rear ends of the slides 29, so that the latter may force the catches above the shoulders 32 to allow the spring 24 to draw the pin 22 and the parts movable therewith towards the rear for the purpose of collapsing the dies 9.

The front ends of the slides 29 have the slots 37 to receive the pins 38 screwed into the body 5. The pins limit the movements of the slides 29. On the outer face of each slide 29 and at its outer end is a block 39 having the longitudinal slot 40 to receive the screw 41 which passes through an outer block 42 seated on the block 39. The screw 41 screws into the adjacent slide 29 and clamps the latter and the two blocks together. The meeting faces of the blocks 39 and 42 have intermeshing teeth 43. The outer ends of the blocks 39 extend beyond the lugs 16 and are connected by screws 45 to the ring 44 which surrounds the body 5 at or just beyond the rear ends of the dies 9, so that, when the threading operation is completed, the article threaded will be engaged by the ring and allow the forward movement of the tap to force the catches against the rear ends of the slides 29 and above the shoulders 32, the spring 24 then automatically causing the dies 9 to collapse as already explained. By loosening the screws 41, the blocks 39 may be moved backwards or forwards to adjust the position of the ring longitudinally, and the slides 29 may be adjusted longitudinally also, the screws being tightened after the adjustments have been made.

The ring has connected to its rear face the blocks 46, on the outer faces of which are seated the adjustable blocks 47, having the slots 48, through which the screws 49 pass into the blocks 46. The rear ends of the blocks 47 are preferably spaced from the collar 13 a distance slightly less than the maximum distance the slides 29 travel. Springs 50 may be used to press the ring 44 outwardly.

A stop collar 51 surrounds the spindle 1 between the bearing 2 and the flange 3. A pair of push-rods 52 are adjustably connected to the collar 51 and project through the flanges 3 and 4 and have their forward ends in the path of the cap 35 when the spindle 1 is moved to the left to withdraw the end of the tap from an article after threads have been cut therein. Springs 54 may surround the rods 52 between the flange 3 and the collar 51 to support the collar when the tap is operated in a vertical position.

With the parts as shown in the drawings, the tap is ready for a threading operation. The catches 33 by engagement with the shoulders 32 cause the collars 13 and 19, the slides 12 and the dies 9 to move to the

right as the spindle is fed to the right. As the spindle is fed to the right it causes the tap to enter the object to be threaded, the threading proceeding in the usual well known manner. At the close of the threading operation, the ring 44 has its right-hand travel stopped by engagement with the end of the said object. The stopping of the travel of the ring 44 also stops the travel of the slides 29 and the blocks 47. The travel of the remainder of the tool continues while the catches 33 ride radially outwardly on the inclined ends of the slides 29 until the catches pass beyond the shoulders 32, whereupon the spring 24, acting through the pin 22 and the collars 13 and 19, quickly pulls the collars 13 and 19 and the slides 12 to the left, the latter collapsing the dies 9 in an evident manner. At the same time the catches 33 ride on the body 5 and to the left of the shoulders 32. In case the spring 24 fails to act as described, the continued travel of the tool will soon bring the collar 13 against the blocks 47, which will give the collar 13 and the parts connected thereto a start to the left, the spring 24 then completing the movement. If the tap is vertical the springs 50 might be omitted, though they might be useful in case the slides 29 or other parts connected thereto should stick.

The dies 9 having been collapsed, the spindle 1 and the tap can without rotation be readily fed to the left in the usual manner to withdraw the tap from the threaded article. Soon after the tap has left the article, the hub 55 of the collar 51 engages the bearing 2 and stops the travel of the collar and the rods 52. Soon the cap 35 engages the rods 52 and stops the travel of the collars 13 and 19 and the slides 12 and the dies 9. The continued travel of the spindle 1 and the body 5 causes the dies 9 to be moved outwardly to their working positions and the shoulders 32 to be moved to the left of the catches 33, which are then pressed into the grooves 31 and in front of the shoulders 32. The catches hold the cap 35, the collars 13 and 19, the slides 12, and the dies 9 in place with the dies expanded. The springs 50 will cause the slides 29 to be moved from beneath the catches so that the latter may be seated as described. During this setting operation the flange 4 has moved backwardly increasing the pull of the spring 24 on the pin 22.

I claim:

1. In a threading device, a longitudinally movable body, collapsible threading dies carried thereby, means locking the dies in expanded positions, means causing the dies to collapse upon release of the locking means, means automatically releasing the locking means upon the advance of the body a predetermined distance, and means automati-

cally causing the resetting of the dies and locking means during the retreat of the body.

2. In a threading device, a longitudinally movable body, means locking the dies in expanded positions, means causing the collapse of the dies upon release of the locking means, an element movable with the body, and means whereby, when the element is stopped 10 during the advance of the body, the locking means is automatically released, and when the element is stopped during the retreat of the body, the locking means is automatically reset.

15 3. In a tapping device having a longitudinally movable body holding collapsible threading dies, means automatically collapsing the dies when the body has advanced a predetermined distance, means automatically 20 expanding the said dies upon the retreat of the body a predetermined distance, and means releasable by the first means for locking the dies in expanded positions.

4. In a tapping device having a longitudinally movable body holding collapsible threading dies, means slidable longitudinally of the body for expanding and collapsing the dies, a spring-pressed catch carried by the said means, a stop engageable by said catch 30 to prevent the collapsing of the dies, a spring tending to actuate the first means to collapse the dies when the catch is released from the stop, means for automatically tripping the catch when the body has advanced a predetermined distance, and means for automatically resetting the said parts with the catch locking against the stop when the body has retreated a predetermined distance.

5. In a tapping device having longitudinal and axially-rotatable movements, a longitudinally movable body, collapsible dies carried thereby, slides carried by the body for expanding and collapsing the dies, means slidable on the body for moving the slides, a spring-pressed catch carried by the said means, a stop on the body arranged to be engaged by the catch and hold the said means in position at which the dies are expanded, a slide automatically movable to release the 45 catch from the slot when the tapping device has moved forwardly a predetermined distance, a spring for moving the said means rearwardly as soon as the catch has been released, and means for automatically moving the said means to locking position upon a movement of the said body rearwardly a predetermined distance.

6. In a tapping device having longitudinal and axially-rotatable movements, a longitudinally movable body, collapsible dies carried thereby, slides carried by the body for expanding and collapsing the dies, means slidable on the body for moving the slides, a spring-pressed catch carried by the said 65 means, a stop on the body arranged to be

engaged by the catch and hold the said means in position at which the dies are expanded, a slide automatically movable to release the catch from the slot when the tapping device has moved forwardly a predetermined distance, a spring for moving the said means rearwardly as soon as the catch has been released, means for automatically moving the said means to locking position upon a movement of the said tapping device rearwardly 70 a predetermined distance, and means for automatically moving the tripping slide from tripping position to permit the catch to be reseated when the body retreats a predetermined distance. 80

7. In a tapping device having longitudinal and axially-rotatable movements, a longitudinally movable body, collapsible dies carried thereby, slides carried by the body for expanding and collapsing the dies, means 85 slidable on the body for moving the slides, a spring-pressed catch carried by the said means, a stop on the body arranged to be engaged by the catch and hold the said means in position at which the dies are expanded, a slide automatically movable to release the catch from the slot when the tapping device has moved forwardly a predetermined distance, a spring for moving the said means rearwardly as soon as the catch has been released, means for automatically moving the said means to locking position upon a movement of the said body rearwardly a predetermined distance, and means for adjusting the throw of the die-operating slides. 95

8. In a tapping device having longitudinal and axially-rotatable movements, a longitudinally movable body, collapsible threading dies carried by the body, slides carried by the body for expanding and collapsing the dies, a slid able rotatable collar on the body at the rear of the dies and connected to operate the slides as the collar moves, a second collar slid able on the body and having a threaded connection to the first collar, 105 a catch carried by one of the collars, a stop carried by the body to lock the said one of the collars when the dies are expanded, a spring urging the catch to locking position, a pin extending through a longitudinal slot 110 in the body and seated in the second collar, a spring to draw the pin rearwardly when the catch is released, means for automatically releasing the catch at the close of a threading operation, and means for automatically resetting the parts in locked position when the body retreats a predetermined distance. 115

9. In a tapping device having longitudinal and axially-rotatable movements, a longitudinally movable body, collapsible threading dies carried by the body, slides carried by the body for expanding and collapsing the dies, a device slid able on the body at the rear of the dies and connected to operate the 125 130

slides as the device moves, a catch carried by the device, a stop carried by the body to lock the device when the dies are expanded, a spring urging the catch to locking position, a pin extending through a longitudinal slot in the body and seated in the device, a spring to draw the pin rearwardly when the catch is released, means for automatically releasing the catch at the close of a threading operation, and means for automatically resetting the parts in locked position when the body retreats a predetermined distance.

10. In a tapping device having longitudinal and axially-rotatable movements, a body, collapsible dies carried thereby, slides carried by the body for expanding and collapsing the dies, means slidable on the body for moving the slides, a spring-pressed catch carried by the said means, a stop on the body arranged to be engaged by the catch and hold the said means in position at which the dies are expanded, a slide automatically movable to release the catch from the slot when the tapping device has moved forwardly a predetermined distance, a spring for moving the said means rearwardly as soon as the catch has been released, means for automatically moving the said means to locking position upon a movement of the said tapping device rearwardly a predetermined distance, and means for automatically resetting the parts in locked position when the body retreats a predetermined distance.

mined distance, and means for giving the said slidable means a positive rearward movement in case the said spring does not initiate the said rearward movement.

11. In a tapping device having longitudinal and axially-rotatable movements, a body, collapsible dies carried thereby, slides carried by the body for expanding and collapsing the dies, means slidable on the body for moving the slides, a spring-pressed catch carried by the said means, a stop on the body arranged to be engaged by the catch and hold the said means in position at which the dies are expanded, a slide automatically movable to release the catch from the slot when the tapping device has moved forwardly a predetermined distance, a spring for moving the said means rearwardly as soon as the catch has been released, means for automatically moving the said means to locking position upon a movement of the said tapping device rearwardly a predetermined distance, means for giving the said slidable means a positive rearward movement in case the said spring does not initiate the said rearward movement, and means for adjusting the last claimed means.

In testimony whereof I hereunto affix my signature this 24th day of November, 1922.

GEORGE E. MILLER.
